UNITED STATES PATENT OFFICE.

ABRAM E. SMITH, OF NEW YORK, N. Y.

TANK-CAR.

1,100,495.

Specification of Letters Patent. Patented June 16, 1914.

Application filed December 15, 1913. Serial No. 809,699.

To all whom it may concern:

Be it known that I, ABRAM E. SMITH, a citizen of the United States, residing in the city of New York, borough of Brooklyn, county of Kings, and State of New York, have invented new and useful Improvements in Tank-Cars, of which the following is a specification.

My invention relates to tank cars, that is, 10 cars generally employed for the transportation of liquids in bulk, and which comprise a horizontally disposed cylindrical tank suitably supported on an underframe which is mounted on trucks.

15 My invention relates more particularly to means for preventing lateral and vertical movement of the tank relatively to its supporting underframe. By my invention I am enabled to dispense with the tank bands 20 and grapple which are generally employed for this purpose.

I will describe a tank car embodying my invention and then point out the novel features thereof in detail.

25 In the accompanying drawings Figure 1 is a diagrammatic view of a tank car embodying my invention; Fig. 2 is a detail view of a portion of a tank and a supporting underframe and showing end elevation 30 means embodying my invention for holding the tank against lateral and vertical movement relatively to the underframe; Fig. 3 is a side elevation of Fig. 2 but partly in section; and Fig. 4 is a detail view of a 35 part embodied in the form of invention illustrated.

Similar letters of reference designate corresponding parts in all of the figures.

40 A designates a tank which is preferably of metal and constructed in any manner well known to the art.

B designates a form of underframe upon which the tank is supported. The underframe B may be of any desired construction, and as here shown it comprises longitudinal center sills b, (only one of which is illustrated) joined together by top and bottom plates δ' . The underframe is mounted on wheeled trucks, suitable center plates 45 δ^2 which are riveted to the center sills, being provided at both ends of the underframe. The tank A should be held against longitudinal movement relatively to the underframe and any desired means known in 50 the art may be employed for this purpose.

A form of such means is shown, described, and claimed in United States Letters Patent No. 768,888, issued August 30, 1904, to J. W. Van Dyke.

The tank A rests in suitable saddles or 60 cradles which are connected to the underframe in any desired manner. As here shown each saddle or cradle is formed in two halves, one such half C, being shown, and all being of the same construction and 65 secured to the underframe in the manner shown in Fig. 2. Rivets c are here shown as being employed to secure the half saddle or cradle to the form of underframe shown. A tension member c' is also preferably em- 70 ployed in connection with this type of underframe which joins the lower portion of the half saddle or cradle with the underframe.

Each half saddle or cradle is provided 75 with a flange c^2 , with which are connected means embodying my invention for holding the tank against vertical and lateral movement relatively to the underframe. These means, as here shown, comprise a section of 80 angle iron D, suitably secured through one of its members to the tank, for example by rivets d, and provided in its other member with one or more openings d' . The openings d' are preferably elongated, as shown 85 which permits of longitudinal expansion of the tank relatively to its underframe without in any way impairing the connection between the angle irons D and the saddles or cradles. One or more bolts d^2 (the number 90 of bolts depending upon the number of openings d') are employed to unite the angles D with the cradles or saddles. These bolts pass through openings in the flange c^2 and they may or may not be elongated as 95 described and through the openings d' , and the bolts are held in the openings by means of nuts d^3 .

What I claim as my invention and desire 100 to secure by Letters Patent is:

1. The combination with a tank of a tank car; an underframe; saddles carried by the underframe and each provided with a flange; angle irons secured to the tank, one for each flange of the saddles, adjacent the flanges of the saddles; and bolts passing through the flanges and angle irons whereby, 105 the tank is held against vertical and lateral movement relatively to the underframe.

2. The combination with a tank of a tank 110

car; an underframe; saddles carried by the underframe and each provided with a flange; angle irons secured to the tank, one for each flange, adjacent the flanges of the 5 saddles and provided with elongated openings; and bolts passing through the said elongated openings and the flanges whereby the tank is held against vertical and longitudinal movement relatively to the under-

frame, but is permitted to have longitudinal movement relatively to the underframe. 10

In testimony whereof I have hereunto signed my name in the presence of two subscribing witnesses.

ABRAM E. SMITH.
